SHACKLE

Leslie G. Ehmann, Portland, Oreg., assignor to
Electric Steel Foundry, Portland, Oreg., a corporation of Oregon

Application August 11, 1939, Serial No. 289,545

2 Claims. (Cl. 59—86)

This invention relates to a securing means, and has special reference to a shackle and pin type of securing means, being particularly directed to an improved locking arrangement for securing a pin against casual displacement from a shackle when in working position.

An object of the invention is to provide a pin for a shackle and the like having mutual interlocking engagement therewith when the pin is in working position.

A further object of the invention is to provide a shackle and the like having a pin readily insertable into working position and readily removable therefrom.

A further object is to provide a shackle and the like having a pin readily inserted or removed by simple manual manipulation without the use of tools and which is secure against casual and accidental displacement.

A further object is to provide a shackle and the like having a readily removable pin, the parts being of rugged construction and designed to operate satisfactorily in the presence of sand, grease, mud, or other foreign materials.

Additional objects and advantages of the invention will become apparent as the description proceeds in connection with the accompanying drawing, it being understood that the drawing is illustrative only and that various changes and modifications may be resorted to without departing from the spirit or scope of the invention; and I deem myself entitled to all such changes and modifications as fall within the scope of the claims hereto appended.

In the drawing:

Figure 1 is a perspective view of a shackle embodying the principles of the invention.

Figure 2 is a fragmentary end elevation of the shackle, taken from the left of Figure 1.

Figure 3 is a perspective view of the pin to be used with the shackle.

Figure 4 is a fragmentary sectional view taken on the line 4—4 of Figure 2, showing the manner of inserting the pin.

Figure 5 is a fragmentary sectional view similar to Figure 4, showing the pin inserted and rotated into working position.

Figure 6 is a fragmentary sectional view through the shackle, showing a hook assembled therewith and in working position.

Figure 7 is a fragmentary sectional view through the shackle, showing an eye of a cable assembled therewith and in working position.

The invention is herein illustrated as applied to a shackle 1 having arms 2 and 3 provided at 55

their extremities with aligned openings 4 and 5. The opening 4 is of generally circular form and is enlarged at its outer end as shown at 6. A groove or slot 7 extends the length of the opening 4, and opens at its end into the enlargement 6, the radial depth of the bottom of the slot being the same as the radius of the enlargement 6. It will be noted in Figure 2 that slot 7 is angularly displaced from alignment with the arms 2 and 3 of the shackle, for reasons presently to be described.

The opening 5 is also generally circular in form, but contains the inwardly-directed arcuate fin 8 extending substantially 180 degrees therearound. In the embodiment illustrated, the fin 8 is axially spaced from the ends of the opening 5, and hence from the opposite faces of the arm 3, as will be seen in Figures 1, 4 and 5. Also, it will be noted that the fin 8 in the opening 5 is disposed angularly opposite the slot 7 in the opening 4. This relationship is best illustrated in Figure 2, and its purpose will be presently described.

A pin, such as illustrated generally at 10, is designed for use with the shackle 1. The pin 10 has a generally cylindrical shank 11 with an enlarged head 12 on one end thereof. Extending along the cylindrical surface of shank 11 is the projection or rib 13, said rib being of such a length, and so located on the shank that when the pin 10 is assembled in working position in the shackle the projection 13 will be disposed between the arms 2 and 3 with suitable clearance, as best shown in Figure 5. The width and height of the projection 13 are such as will facilitate a loose, sliding fit within the slot 7 when the pin 10 is inserted through the opening 4.

The end of the pin opposite the head 12 is formed to the shape of a cylinder of reduced diameter, as shown at 14. Formed integrally with the reduced cylindrical portion 14 is the outwardly-directed arcuate fin or lip 15, extending substantially 180 degrees therearound, and being in angular alignment with the projection 13 for reasons which will presently appear.

To insert the pin into the shackle it will be seen necessary only to start the small end 14 of the pin through the opening 4, at the same time rotating the pin until the projection 13 readily slides through the slot 7. When the pin has been rotated so that projection 13 is received through the slot 7, it will be seen that fin 15 will pass beyond the fin 8, and the pin will slide to the right, as the views are taken in Figures 1, 4 and 5, until head 12 seats in the enlarged

opening 6. When the head is thus seated, and the fin 8 has passed beyond fin 15, the pin may be rotated into working position, as shown in Figure 5, in which position the projection 13 is locked behind the non-slotted portion of the periphery of opening 4, and the fin, or lip, 15 is locked behind the complementary fin 8 on the shackle, preventing unintentional displacement of the pin 10. It will be seen that the fins 8 and 15 may be disposed in a different angular relationship with respect to slot 7 and projection 13, the only requirement being that the two fins clear each other when the pin is inserted into position in the shackle, and that they enter into interlocking engagement with each other when the pin 10 is rotated into a working position.

When the pin 10 has been inserted and rotated into working position in the manner just described, and as illustrated in Figure 5, it will be seen that the interlocking engagement of fins 8 and 15 not only prevents accidental displacement of the pin, but also insures against spreading of the shackle arms 2 and 3 under load, and consequent disengagement of the end 14 of the pin from the opening 5. Instead of the single fin 8 on the shackle and the single fin 15 on the pin, there may be provided a plurality of fins 8 on the shackle and a plurality of fins 15 on the pin, the fins being disposed so that the pin may be inserted into the shackle and rotated into locking position in the same manner as shown for the fins 8 and 15.

Once the pin 10 has been rotated into locked, or working position accidental rotation back to unlocking position is effectively prevented by interlocking engagement of the rib or projection 13, with a load supporting means, as illustrated in Figures 6 and 7. If a hook is to be used on the shackle such as the hook 16 of Figure 6, the eye of the hook is grooved as at 17 to receive the projection or rib 13 on the pin 10, causing the pin to be keyed to the hook and to rotate therewith. Thus it will be seen that any working position assumed by the hook under load will necessarily determine the position of pin 10 and prevent rotation of the projection 13 into alignment with slot 7. This is true because the slot 7 is displaced by a relatively small angle from the plane of the arms 2 and 3, as best shown in Figure 2; the angle of this displacement being determined by the angle between the plane of the shackle arms and the hook when the latter is swung back to the limit of its movement. When swung back to the limit of its movement, the hook will contact the body of the shackle, assuming a position which may be called a relaxed position. The shackle is designed so that as the hook closely approaches the above-described limit of movement, or relaxed position, the projection 13 will come into alignment with slot 7, the fins 8 and 15 will have cleared each other, and the pin 10 may be withdrawn.

Load supporting means other than a hook may be used with the shackle 1, but it is intended that the operation be the same as that just described for hook 16. For instance, a cable eye may be used directly on the pin 10, as shown in Figure 7. In this case the eye may permit a limited relative rotation between the eye and the pin, but accidental rotation of the pin to unlocking position will be effectively prevented. Figure 7 shows a cable 20 having a small eye 21 looped over the pin 10, the eye 21 restraining the pin to the small amount of relative rotation permitted by movement of the projec-

tion 13 between the full line position and the dotted line position. To rotate the pin into unlocking position it is necessary either to swing the cable 20 back against the shackle to a position corresponding to the described relaxed position of hook 16, or to loosen the eye 21 sufficiently to allow the pin 10 to be rotated by hand to the desired position.

It is to be understood that the pin 10, when 10 fully inserted as shown in Figure 5, is free for unlimited rotation and offers substantially no resistance to pivotal movement of either hook or cable or any other supporting means that may be used therewith. The angular position of the load relative to the plane of the shackle alone determines the orientation of the pin 10 until such load is removed, whereupon the pin may be rotated by hand to unlocking position, and withdrawn from the shackle. By positioning the slot 7 angularly close to the plane of the shackle arms 2 and 3, as described, it is found that accidental unlocking of the pin from the shackle is effectively prevented under actual working conditions. While the best results have been achieved by positioning the slot 7 as illustrated in the preferred embodiment, the invention may be practiced with the slot inclined anywhere between 10 degrees and 80 degrees from the plane of the arms 2 and 3.

From Figure 5 it will be seen that when the pin is in assembled and locked relationship with the shackle there are no projecting parts to catch in obstructions, foul lines, or scoop up foreign material as the shackle is dragged over the ground or sea bottom. The head 12, being contained in the recess or enlarged opening 6, presents a smooth surface continuous with the outer face of arm 2. Likewise the end 14, together with lip or fin 15, presents a substantially smooth surface continuous with the outer surface of arm 3.

While the preferred embodiment of applicant's securing means is illustrated as applied to a pin and shackle combination, it is to be understood that the invention is not limited thereto, as it may be used wherever a coupling or securing function is accomplished by means of a pin insertable through aligned openings. This type of securing means is rugged, foolproof, simple to construct, and simple to operate. It has particular utility in connection with heavy work such as found in the logging industry and in undersea operations where unwieldy cables must be quickly attached and removed from various types of supporting means under adverse conditions, and in the presence of mud, grit, and other foreign matter.

The invention may be used either in its entirety or in part, and either with or without modifications, in any construction requiring a readily insertable and detachable pin, and I deem myself entitled to all such uses, modifications and variations as fall within the spirit and scope of the appended claims.

Having now described my invention and in what manner the same may be used, what I claim as new and desire to protect by Letters Patent is:

1. A shackle having a pair of arms, aligned openings in said arms, one of said openings being enlarged at the outer end thereof to form a recess in the outer surface of one of said arms, a slot extending through said one opening and opening into said recess, the radial depth of said slot not exceeding the boundary of said recess, said slot being angularly displaced from alignment with

said arm, the other of said openings containing an inwardly-directed, arcuate fin extending partially therearound, and a pin adapted to fit in said openings, said pin having a projection on the shank thereof insertable through said slot, said pin having a head thereon adapted to fit in said recess so as to close said slot and form substantially a smooth surface continuous with said outer surface of said one arm, said pin terminating in a reduced portion having an arcuate fin extending partially therearound and adapted to form substantially a smooth surface continuous with the outer surface of the other arm, said shank extending into and being of a size to fill the other of said openings.

2. A shackle having a pair of arms, aligned openings in said arms, one of said openings being enlarged at the outer end thereof to form a recess in the outer surface of one of said arms, a

slot extending through said one opening and opening into said recess, the radial depth of said slot not exceeding the boundary of said recess, the other of said openings containing an inwardly-directed, arcuate fin extending partially therearound, and a pin adapted to fit in said openings, said pin having a projection on the shank thereof insertable through said slot, said pin having a head thereon adapted to fit in said recess so as to close said slot and form substantially a smooth surface continuous with said outer surface of said one arm, said pin terminating in a reduced portion having an arcuate fin extending partially therearound and adapted to form substantially a smooth surface continuous with the outer surface of the other arm, said shank extending into and being of a size to fill the other of said openings.
